516-4

H-1-5

FIG. 1 is a top plan view of an electrical cable for gaseous discharge panel showing my new design.

FIG. 2 is a bottom plan view of FIG. 1.

FIG. 3 is an enlarged side elevational view thereof, the center being cut away for convenience of illustration.

FIG. 4 is a top plan view of a modified form of the electrical cable for gaseous discharge panel as shown in FIG. 1.

FIG. 5 is a bottom plan view of the modification shown in FIG. 4.

I claim:

The ornamental design for an electrical cable for gaseous discharge panel, as shown and described.
